(57) **CLAIM**

The ornamental design for a fork lift apparatus for mounting on a three-point hitch, as shown and described.

DESCRIPTION

FIG. 1 is a right front perspective view of the fork lift apparatus for mounting on a three-point hitch;

FIG. 2 is a left rear perspective view thereof;

FIG. 3 is a lower, left rear perspective view thereof;

FIG. 4 is a left side elevational view thereof, the right side elevational view being a mirror image thereof;

FIG. 5 is a top plan view thereof;

FIG. 6 is a bottom plan view thereof; and,

FIG. 7 is a front elevational view thereof.
